COMBINED GOLF CLUB HANDLE AND SHAFT

Lawrence E. Kindred, 1749 Crofton Parkway,
Crofton, Md. 21113

Filed Nov. 5, 1974, Ser. No. 521,071

Term of patent 14 years

Int. Cl. D21—02

U.S. Cl. D34—5 GS

FIG. 1.

FIG. 2.

FIG. 3.

FIG. 1 is a pictorial view of a combined golf club handle and shaft, showing my new design.

FIG. 2 is an elevation view of the combined golf club handle and shaft shown in FIG. 1.

FIG. 3 is a top plan view of the combined golf club handle and shaft shown in FIG. 1.

I claim:

The ornamental design for a combined golf club handle and shaft, as shown and described.
